UNITED STATES PATENT OFFICE.

WILLIAM LINDSAY, OF CHICAGO, ILLINOIS.

AGITATING DEVICE.

1,267,562.

Specification of Letters Patent. Patented May 28, 1918.

Application filed August 30, 1917. Serial No. 188,951.

To all whom it may concern:

Be it known that I, WILLIAM LINDSAY, a citizen of the United States, residing at Chicago, in the county of Cook and State of Illinois, have invented certain new and useful Improvements in Agitating Devices, of which the following is a description, reference being had to the accompanying drawings, forming a part of this specification, 10 in which corresponding numerals of reference in the different figures indicate like parts.

The object of my invention generally stated, is to provide a simple, novel and effective means for imparting a gyratory or shaking motion to a sieve, structure or container for the purpose more especially of sifting or screening comminuted materials, such, for example, as molders' sand, enameling 20 and other powder, cement, flour or the like, or for agitating any structure containing any substance, liquid or compound.

A further object is to so construct said device that the gyratory stress or force may be absorbed directly by the load and not by the structure or frame by which it may be supported or suspended.

While it is old in various instances and ways to suspend gyratory structures so as to be free to swing in mid-air from one or more points of suspension, I have discovered that the manner of applying the gyratory force thereto is of the utmost importance if satisfactory results are to be produced. If 35 applied to the structure in a positive way so that the driven gyratory element is relied upon to positively control the extent and character of the movement, regardless of load variations, or the relative proportions 40 between the load and the actuating force, the noise and jar, as well as the power required, will be excessive, the effectiveness of the device impaired and its period of usefulness shortened.

If the structure to be agitated be suspended from a single point and the gyratory force applied between that point and the load, it has been found necessary to make the suspending frame rigid in order to 50 transmit movement through it to the load; in which case, experience has demonstrated that if a sufficiently high speed be applied to the gyratory element (usually an unbalanced weight upon a vertical shaft) to produce effective agitation, the metal frame

will be caused to crystallize and will soon become useless. My main purpose, therefore, is to overcome these objections by supplying novel agitating means and so applying it as to cause the load, *per se*, to directly 60 absorb the stress or shock; or, in other words, to coact with the gyratory element to establish a rhythmic movement between the two, thereby establishing a gyratory relation adapted to be automatically varied 65 in conformity to load variations and resulting in economy of power while eliminating undue noise and jar and preventing injurious stress upon any of the coacting parts.

Again, it is my purpose to dispense with 70 the use of a shaft and unbalanced weight, which necessitates a frame rigid with the sifter, and in lieu thereof, to provide a gyratory motor element so constructed and arranged as to permit the sifter to be suspended from one or more points and upon one or more flexible elements, so that the gyratory character of the stresses may be varied when desired to produce a compound movement, such, for example, as a wabbling 80 or oscillatory gyration of the load in addition to an orbital movement around the axis of suspension and to vary the degree of said wabbling action so as to render the device more effective in the treatment of different materials.

I accomplish said objects generally by freely supporting or preferably suspending in mid-air the structure to be agitated and connecting therewith a motor which 90 shall be so mounted within the structure that its body as an entirety, may be caused to rotate upon an axis eccentric to the axis of the motor so as to produce an agitation or gyratory movement of the load, the extent and character of which may vary in proportion to the relative speed and weight of the motor, the relative point or points of suspension, the length of the suspending element, the weight of the load and the angle of variance, if any, between the axis of rotation of the motor casing and the gyratory axis or orbit of the load; all of which is hereinafter more particularly described and definitely pointed out in the claims. 105

In the drawings,

Figure 1, is an elevation of a suspended frame having a screen thereon, shown in section, together with my improved gyratory motor-member, 110

Fig. 2, is an enlarged vertical central section of the motor member and casing therefor,

Fig. 3, is a section taken upon the line 3—3, Fig. 2, viewed as indicated by the arrows there shown,

Fig. 4 is an enlarged central vertical sectional view in detail showing the pivotal support for the suspending chains,

Fig. 5, is a view partly in elevation and partly in section, showing a modified construction, and

Fig. 6, shows a modified construction in which the casing containing the motor is shown with means for adjusting it to varying positions for varying the angle of the axis of the motor body with respect to the gyrating axis of the load.

Referring to the drawings, 1 indicates generally a frame consisting preferably of three or more metal bars or tubes 2, tapped into and extending radially from a central cylindrical casing 3, the purpose of which will be presently explained. The arms 2 are bent upwardly as shown at 4, and the upper ends thereof, which are equidistant from the center, are connected by means of chains 5, with a tiltable supporting member 6, Figs. 1 and 4, having a central socket bearing therein adapted to fit loosely upon a ball 7, formed upon the lower end of a suspending link 8, the upper end of which link is connected with a supporting member 9 adapted to be connected to a stationary support. Rigidly attached to the radial frame members, is a ring like member 10 having a horizontal flange portion 11, upon which is supported a sieve frame 12, having the usual screen or sieve 13 therein. Said frame is adapted to be rigidly secured within the ring 10 so as to be removed as desired.

The agitating or gyratory element consists preferably of an electric motor having its frame pivotally mounted within the central casing 3 upon bearings eccentric to the axis of its armature and so connected with said casing as to cause the motor frame to rotate upon said eccentric axis so that the weight of the motor *per se*, may serve to impart a gyratory action to the casing 3 and through it to the entire structure.

Located within the casing 3, is a motor frame consisting preferably of a hollow cylindrical metal member 14, having short wrist-pins or journals 15, rigidly attached to or formed upon its opposite ends which journals are in alignment with each other and eccentric to the axis of the casing 14. The journals 15 are preferably mounted in ball bearings 16 upon the end members 17 and 18 respectively of the casing 3.

Attached to the upper end member 17, by means of screws 19, is a ring 20 formed from compressed fiber or other suitable in-

sulating material within which is embedded metal contact rings 21 and 22, both of which are concentric with the axis of the journals 15. The rings 21 and 22, respectively, are connected by means of leads 23 and 24 with a source of electric energy not shown. Said leads, properly insulated, are carried outwardly through one of the tubes 2 and thence upwardly along one of the chains 5, as shown in Fig. 1 to said source. Brackets or arms 25 and 26, Fig. 2, are rigidly attached to the casing 14 and provided with brushes 27 and 28 from the latter of which a lead 29 is connected with the winding of a field-magnet 30 within the motor casing, which field is connected at 31 with a brush 32, in contact with a commutator 33 upon a rotary armature 34. A like brush 35 is connected through a lead 36 with the brush 27, thereby completing the circuit in the usual way through the field.

The armature shaft 37 is journaled in ball-bearing 38, 39 fitted concentrically in opposite ends of the casing 14. A pinion 40, Figs. 2 and 3, keyed to the upper end of the armature shaft, has its teeth fitted to mesh with those of an annular gear 41, rigidly attached to the end member 17 of the casing 3, and concentric with the axes of the journal members 15, so that when the armature is rotated the pinion 40 will be caused to travel around the axial center 15, thereby causing a rotary movement of the motor body upon an eccentric axis, which serves to impart a gyratory movement to the casing 3, and, through it, to the frame and sieve around the axial center of the load.

Numerous exhaustive experiments and many years of experience in connection with sifting appliances have convinced me that different treatment is required for the successful sifting of different materials. Dry coarse sand and fine 'wet molders' sand act differently; and the same kind of agitation which would be most effective with them would cause a heavy impalpable powder, such, for example, as enameling powder or other lead oxid, to pack in such a way as to greatly retard if not to entirely prevent effective sifting. For the coarser materials, the more varied and erratic the motion, the better; while for the finer ones, there appears to be a kind of rhythmic action which must be imparted to the entire mass to render the movement of the minute particles uniform and free. By extending the casing 3 with the contained motor well below the structure substantially as shown in Fig. 1, and using flexible suspension means, not only will there be produced a gyratory movement in an orbit around the axial center of the load and in a horizontal plane, but in addition thereto, a tilting or wobbling movement will be imparted to the

sieve sufficient to successively cause a considerable slack in each suspending chain. During the instant of such yielding action, the weight, being supported by the other 5 two chains, the centrally pivoted suspending member 6 is depressed upon one side, while the slack of the chain upon the other allows that side to tilt upwardly in conformity to the wobbling or oscillatory movement of the sieve. The pivotal movement of the part 6 tends to neutralize the shaking action upon the suspending member 8 and the jar incident to the gyratory movement of the motor frame is absorbed, as it 10 should be, by the load.

For purposes of coarse screening it may be found desirable to increase the wobbling action of the sieve. This may be accomplished by tilting the eccentric axis of the 20 motor frame at an angle to the axis of suspension of the sieve.

As shown in Figs. 1 and 2 the axis of suspension of the sieve and the axis of the motor member coincide. By tilting the casing 25 so that the plane of its upper face may be oblique to that of the horizon or, which would amount to the same thing, by tilting the body of the motor within said casing, so that the axis of the motor body may be 30 at an angle oblique to a horizontal plane, the wobbling action of the sieve may be increased to any desired degree without lessening the gyratory orbit around the axis of the load. Such a construction is illustrated 35 in Fig. 6 in which the casing 42 corresponding to the casing 3 in the other views, instead of being rigidly attached directly to the frame members 2, is jointedly attached as shown at 43 to a lug 44 upon the under side 40 of a plate 45 to which the frame member 2 is rigidly attached. An adjusting screw 46, connected at one end to the part 45 through a swiveled connection 47, is tapped into a lug 48 upon said casing so that the 45 casing 42 and with it the axis of the motor body within, may be inclined at any desired angle to the plane of the part 45.

In Fig. 5 I have shown a modified construction more especially adapted for the 50 sifting of very fine and heavy powders such for example as lead oxids, in which the casing 49 containing the gyratory motor is extended upwardly through the body of the sieve so as to apply the gyratory force as 55 nearly as possible in the horizontal plane of the load, thereby avoiding the wobbling action described while maintaining the orbital movement.

I do not wish to be limited to the exact 60 construction shown inasmuch as it may be varied without departing from the spirit of the invention; nor do I wish to be limited to electrical energy for actuating the motor.

Having thus described my invention, I claim:

65

1. A device of the character described, comprising, in combination a freely movable structure, a motor mounted thereon upon an axis eccentric to the axis of the body of said motor, and means interposed between the 70 motor shaft and said structure and operatively connected with them for imparting rotary motion to said motor body.

2. An agitating device, comprising, in combination, a structure supported to permit free movement thereof, a motor having its frame rotatively mounted upon said structure upon an axis eccentric to that of said frame and operative connecting means between said motor frame and structure to cause rotation of said motor frame for imparting a gyratory movement to said structure.

75

3. An agitating device, comprising, in combination, a structure freely supported to 85 permit it to be moved around a given axis, an electric motor having journals arranged eccentric to the axis of its frame, said journals being mounted in bearings in the structure, an armature shaft and gears for operatively connecting said shaft with said structure, whereby the rotation of the motor upon said eccentric axis may serve to impart a 90 gyratory movement to said structure.

95

4. A device of the class described, comprising, in combination a structure freely supported to permit it to move around a given axis, an electric motor having its frame rotatably mounted upon said structure upon an axis eccentric to the axis of 100 said frame but substantially concentric with that of said structure and means interposed between the motor shaft and said structure for imparting rotary motion to said motor frame around said eccentric axis.

105

5. A device of the class described, comprising, in combination, a structure to be agitated, flexible means for suspending the same to permit it to swing in an orbit around a vertical axis while free to take a different motion in addition to that of said orbital movement, an electric motor having its frame rotatably mounted upon said structure upon an axis eccentric to the axis of said frame, said frame being so adjusted 115 with reference to said structure as to cause a wobbling action of the latter, and means in operative connection with the motor shaft and structure for imparting a rotary movement to said motor frame around said eccentric axis.

110

6. An agitating device, comprising, in combination, a structure freely suspended by flexible means to permit a compound gyratory movement thereof, an electric motor 125 having its frame or casing rotatably mount-

120

125

- ed upon said structure upon an axis eccentric to that of said frame and means in operative connection with the motor shaft for imparting rotary movement to said motor frame, the relation of the frame to the structure being such as to impart a wobbling movement to the latter in addition to that around said axial center.
7. An agitating device comprising a structure supported to permit free movement in an orbit around a given axis and an electric motor operatively connected with the structure and having its casing journaled in said structure upon an eccentric axis to cause rotation of said motor casing upon said axis.
8. An agitating device comprising a structure supported to permit free movement in an orbit around a given axis and an electric motor having its casing journaled in said structure upon an eccentric axis to cause rotation of said motor casing upon said axis, said motor being located substantially in the horizontal plane of the load.
9. An agitating device comprising a structure supported to permit a movement thereof in an orbit around a fixed axis and an electric motor journaled in said structure upon an axis eccentric to that of the motor body, the armature of said motor being in operative connection with said structure to cause rotation of the motor body upon said eccentric axis for imparting a gyratory movement to said structure.
10. An agitating device comprising a structure supported to permit a movement thereof in an orbit around a given axis and an electric motor journaled in said structure upon an axis eccentric to that of the motor body, the armature of said motor being in operative connection with said structure to cause rotation of said motor body upon said eccentric axis for imparting a gyratory movement to said structure, a portion at least of said motor body being below the level of said structure.
11. An agitating device comprising a structure supported to permit free movement in an orbit around a fixed axis and a secondary movement in addition thereto, an electric motor operatively connected with the structure and having its casing journaled in said structure upon an eccentric axis to cause rotation of said motor casing upon said axis and means for adjusting said axis at an angle oblique to said fixed axis for causing a wobbling movement of said structure in addition to the orbital movement thereof around said fixed axis.
12. An agitating device, comprising a structure supported to permit free movement around the axis of support, an electric motor journaled in said structure upon an axis eccentric to the axis of the body of said motor, and a stationary gear upon said structure concentric with the armature shaft and in operative engagement with a gear upon said shaft.
13. In a gyratory structure, the combination with a movably supported element to be agitated, of a driving element comprising an electric motor rotatably mounted upon said movably supported element, upon a common axis, the axis of the rotor of said driving element being arranged eccentrically to the axis of said movably supported element and in operative connection therewith to impart a gyratory movement thereto.
14. An agitating device, comprising a freely movable structure, a motor journaled in said structure upon an axis eccentric to that of the motor body, a motor shaft concentric with said body and interposed gears for operatively connecting the same with said freely movable structure.

In testimony whereof, I have signed this specification in the presence of two subscribing witnesses, this 28th day of August, 1917.

WILLIAM LINDSAY.
